EDWIN W. GOESER AND WILLIAM D. DAVIDSON, OF LOS ANGELES, CALIFORNIA, AS
SIGNORS, BY MESNE ASSIGNMENTS, TO EMSCO DERRICK & EQUIPMENT COMPANY,
OF LOS ANGELES, CALIFORNIA, A CORPORATION OF CALIFORNIA.

ROTARY TABLE.

Application filed March 13, 1924. Serial No. 698,895.

This invention relates to rotary well drilling equipment and relates particularly to the construction of the rotary machine commonly termed rotary table.

5 The rotary table as now employed, provides a base having a vertical opening therethrough. On this base is mounted a circular rotary member or table proper which has a central opening and revolves in alignment with the opening through the base. Between the table and base, it is customary to employ some type of roller bearing so that friction may be kept at a minimum, this bearing being preferably in the form of 10 conical steel rollers set in annular races which are mounted concentric with the openings through the table and the base. In rotary drilling, a cementing mixture in the form of a thin mud is forced downwardly through the string of drill pipe which the rotary machine is arranged to drive. It often occurs that this rotary mud and various other muddy mixtures from the well are split over the rotary machine, such materials 15 entering into the bearing and causing a rapid wear therein.

It is an object of the invention to provide a rotary table in which the bearing elements are well protected from entrance 20 of abrasive materials. The object is attained partly in the use of a hold down ring having a continuous downwardly extending cylindrical apron which covers the opening of the space between the bearing base and the table 25 through which foreign substances ordinarily enter the bearing; and through the use of a cylindrical projection which extends downwardly from the table across the inner face of the bearing and across the inner face of 30 the opening through the base; thus substantially closing both the inner and outer openings of the bearing space so that mud may not enter into the bearing.

A further object of the invention is to 45 provide a means for centralizing the table with the base and forming bearing surfaces between the centralized members; and in addition thereto incorporating improved means for lubricating these bearing surfaces. 50 The especial advantages of the invention and further objects thereof will be made evident hereinafter.

Referring to the drawings which are for illustrative purposes only,

Fig. 1 is a partially sectioned side elevation of a rotary machine embodying the features of the invention. 55

Fig. 2 is an external elevation of the forward end of the rotary machine shown in Fig. 1. 60

Fig. 3 is a section taken as indicated by the line 3—3 of Fig. 1.

In the drawings 11 represents a base from which there extends a base extension 12. The member 11 is provided with a substantially centralized bore 13 and is provided with a counter-bore 15 in its upper face so as to receive a lower annular bearing race 16 arranged to receive conical rollers 17 which operate between the bearing race 16 and an upper bearing race 18 which is carried in an annular channel 19 in the lower face of a rotary table 21. The table 21 is equipped with bevel gear teeth 22 whereby the table may be rotated from a bevel pinion 23 mounted on a drive shaft 24 which extends through bearings 25 and has a sprocket 26 or other drive means associated therewith. 70

The rotary table 21 is equipped with a centralized square opening 27, the lower portion of which opening 27 is defined by a downwardly extending cylindrical flange or wall 28 having an external face 29 which forms a close running fit with the bore 13 of the base and the inner circular face 31 of the race 16. Directly beneath the flange 32 of the table 21 which carries the bevel gear teeth 22, is turned a groove 33, thus forming at the lower edge of this groove a shoulder 34 which is engaged by the inwardly turned lip 36 of the hold down ring 37 which consists of a pair of semi-cylindrical co-operating members 39 and 40 which, when bolted together as indicated at 41 in Figs. 2 and 3 forms a continuous cylindrical apron 43, Fig. 1, extending downwardly over the outer face 44 of the table 21 and over the outer opening of the bearing space 45 between the base 11 and the table 21, and overlapping the upper edge 46 of the base 11 so that any materials coming in contact with the outer face of the hold down ring will be directed past the outer opening of the space 45 and will therefore prevent entrance of foreign materials into the annular bearing 55 between the base 11 and the table 21. 100

The cylindrical flange 28 which extends 105

The cylindrical flange 28 which extends

downwardly from the table 21, within the bore 13 of the base, prevents entrance of substances into the inner openings of the bearing space. On the cooperating member 5 39 of the hold down member 37 is formed an oil reservoir 50 equipped with a cover 51 and having oil passages 52 through which oil is delivered through the lip 36 into the space 53 between the inner edge of the lip 10 and the bottom of the annular groove 33 from whence the oil moves downwardly between the inner face of the apron 43 and the cylindrical face of the lower portion of the table 21 from whence it flows inwardly 15 into the lower bearing race 16 where in the conical rollers 17 are thereby lubricated, the overflow from the bearing race passing downwardly between the cylindrical flange 28 and the face of the bore 13, 20 thus lubricating the bearing which is formed between the lower portion of the cylindrical flange 28 and the bore 13. An oil reservoir 54 is provided on the base 11 to assist in lubricating the race 17 and the flange 28.

25 The hold down ring 37, as will be seen, is continuous in form and is secured to the base 11 by bolts 55 which extend downwardly through the outwardly extending flanges 56 formed at the lower edge of the 30 hold down ring, these flanges resting on shims 57, Fig. 2, which may be adjusted at various times to change the relative positions between the lip 36 of the hold down ring 37 and the shoulders 34 of the rotary table, thus making it possible to keep the 35 rotary table in most efficient working adjustment.

We attach particular importance to the method of aligning the members 39 on the 40 base 46. It will be noted that the continuous cylindrical apron 43 projects downwardly outside a lip formed on the base 46, the lip fitting tightly inside the apron 43. This accurately aligns the members 39 with relation to the base 46 and, since the table 21 bears on the hold down members 39, all side thrusts on the table are directly transmitted to the base independently of the hold down bolts 55.

50 By providing a lip on the base which projects up inside the table we provide a construction which absolutely prevents mud from entering the space in which the rollers 17 turn, and we also prevent the lubricant carried in this space from escaping.

We claim as our invention:

1. In a rotary, the combination of: a base member having a central opening therethrough; a table; bearing means supporting said table on said base; a hold down bracket fitting upon a bearing formed on the periphery of said table; a lip extending inwardly from said hold down bracket and engaging a shoulder formed on said table in such a manner as to limit any upward move-

ment of said table away from said base, said hold down bracket completely surrounding and enclosing said bearing means; and means for rigidly securing said hold down bracket to said base. 70

2. In a rotary, the combination of: a base member having a central opening therethrough; a table; bearing means supporting said table on said base; a member secured to said table extending downwardly and fitting closely in the central opening of said base; a hold down bracket fitting upon a bearing formed on the periphery of said table; a lip extending inwardly from said hold down bracket and engaging a shoulder formed on said table in such a manner as to limit any upward movement of said table away from said base, said hold down bracket completely surrounding and enclosing said bearing means; and means for rigidly securing said hold down bracket to said base. 75

3. In a rotary, the combination of: a base member having a central opening therethrough; a table; bearing means supporting said table on said base; a hold down bracket fitting upon a bearing formed on the periphery of said table; a lip extending inwardly from said hold down bracket and engaging a shoulder formed on said table in such a manner as to limit any upward movement of said table away from said base, said hold down bracket completely surrounding and enclosing said bearing means; a lip projecting upwardly from said base member into a channel formed in said hold down bracket; and means for bolting said hold down bracket to said base. 80

4. In a rotary machine, the combination of: a base member having a central opening therethrough; a rotary table; a primary axial bearing rotatably supporting said table on said base; a hold down bracket shaped to form an annular hood substantially covering the exterior opening between said base and said table; means for centering said bracket relative to said base; means for securing said bracket to said base; means for forming a secondary axial bearing between said table and said bracket opposing said primary axial bearing; and means for forming a radial bearing between said table and said bracket. 105

5. In a rotary machine, the combination of: a base member having a central opening therethrough; a rotary table; a primary axial bearing rotatably supporting said table on said base; a hold down bracket shaped to form an annular hood substantially covering the exterior opening between said base and said table but permitting a 110 flow of lubricating oil from the exterior downwardly between said bracket and said table to said primary axial bearing; means for centering said bracket relative to said base; means for securing said bracket to 115

- said base, an oil-tight fit being formed between said bracket and said base; means for forming a secondary axial bearing between said table and said bracket opposing said primary axial bearing; and means for forming a radial bearing between said table and said bracket, said radial bearing being disposed in the line of said flow of lubricating oil.
- 10 6. In a rotary machine, the combination of: a base member having a central opening therethrough; a rotary table; a primary axial bearing rotatably supporting said table on said base; a hold down bracket shaped to form an annular hood substantially covering the exterior opening between said base and said table but permitting a flow of lubricating oil from the exterior downwardly between said bracket and said table to said primary axial bearing; means for centering said bracket relative to said base; means for securing said bracket to said base, an oil-tight fit being formed between said bracket and said base; means for forming a secondary axial bearing between said table and said bracket opposing said primary axial bearing; and means for forming a radial bearing between said table and said bracket, said radial bearing and said secondary axial bearing being disposed in the line of said flow of lubricating oil.
- 15 7. In a rotary machine, the combination of: a base member having a central opening therethrough; a rotary table; a primary axial bearing rotatably supporting said table on said base; a hold down bracket shaped to form an annular hood substantially covering the exterior opening between said base and said table but permitting a flow of lubricating oil from the exterior downwardly between said bracket and said table to said primary axial bearing; means for centering said bracket relative to said base; means for securing said bracket to said base, an oil-tight fit being formed between said bracket and said base; means for forming a secondary axial bearing between said table and said bracket opposing said primary axial bearing; and means for forming a primary radial bearing between said table and said bracket, said primary radial bearing being disposed in the line of said flow of lubricating oil; and means for forming a secondary radial bearing between said table and said base which is of smaller radius and disposed at a lower level than said primary axial bearing.
- 20 8. In a rotary machine, the combination of: a base member having a central opening therethrough; a rotary table; a primary axial bearing rotatably supporting said table on said base; a hold down bracket shaped to form an annular hood substantially covering the exterior opening between said base and said table but permitting a flow of lubricating oil from the exterior downwardly between said bracket and said table to said primary axial bearing; means for centering said bracket relative to said base; means for securing said bracket to said base, an oil-tight fit being formed between said bracket and said base; means for forming a secondary axial bearing between said table and said bracket opposing said primary axial bearing; and means for forming a primary radial bearing between said table and said bracket, said primary radial bearing being disposed in the line of said flow of lubricating oil; and means for forming a secondary radial bearing between said table and said base which is of smaller radius and disposed at a lower level than said primary axial bearing, the overflow of said oil from said primary axial bearing lubricating said secondary radial bearing.
- 25 9. In a rotary machine, the combination of: a base member having a central opening therethrough; a rotary table; a primary axial bearing rotatably supporting said table on said base; a hold down bracket shaped to form an annular hood substantially covering the exterior opening between said base and said table; means for centering said bracket relative to said base; means for securing said bracket to said base; means for forming a secondary axial bearing between said table and said bracket opposing said primary axial bearing; and means for forming a radial bearing between said table and said bracket, said radial bearing being disposed in the line of said flow of lubricating oil.
- 30 10. In a rotary machine, the combination of: a base member having a central opening therethrough; a rotary table; a primary axial bearing rotatably supporting said table on said base; a hold down bracket shaped to form an annular hood substantially covering the exterior opening between said base and said table; means for centering said bracket relative to said base; means for securing said bracket to said base; means for forming a secondary axial bearing between said table and said bracket opposing said primary axial bearing; and means for forming a radial bearing between said table and said bracket, said radial bearing being disposed in the line of said flow of lubricating oil.
- 35 11. In a rotary machine, the combination of: a base member having a central opening therethrough; a rotary table; a primary axial bearing rotatably supporting said table on said base; a hold down bracket shaped to form an annular hood substantially covering the exterior opening between said base and said table; means for centering said bracket relative to said base; means for securing said bracket to said base; means for forming a secondary axial bearing between said table and said bracket opposing said primary axial bearing; and means for forming a radial bearing between said table and said bracket, said radial bearing being disposed in the line of said flow of lubricating oil.
- 40 12. In a rotary machine, the combination of: a base member having a central opening therethrough; a rotary table; a primary axial bearing rotatably supporting said table on said base; a hold down bracket shaped to form an annular hood substantially covering the exterior opening between said base and said table; means for centering said bracket relative to said base; means for securing said bracket to said base; means for forming a secondary axial bearing between said table and said bracket opposing said primary axial bearing; and means for forming a radial bearing between said table and said bracket, said radial bearing being disposed in the line of said flow of lubricating oil.

In testimony whereof, we have hereunto set our hands at Los Angeles, California, on this 3rd day of March, 1924.

EDWIN W. GOESER.
WILLIAM D. DAVIDSON.
